VARIABLE-OUTPUT HYDRAULIC PUMP

Lawrence Leech, Ryde, England

Application February 19, 1948, Serial No. 9,348
In Great Britain November 27, 1946Section 1, Public Law 690, August 8, 1946
Patent expires November 27, 1966

5 Claims. (Cl. 103—37)

1

This invention relates to a variable-output hydraulic pump of the kind having a rotor with a circle of axially-extending cylinder bores therein, and plungers carried in the bores co-operating with a cam ring so as to be successively reciprocated on rotation of the rotor, the cam ring being adjustable to vary the output.

My main object is to provide a pump of this kind which is pressure-balanced in a very satisfactory manner and of which the control can be very conveniently effected.

According to the invention, each of the cylinder bores, in the rotor, has a pair of plungers therein biased away from one another respectively to contact multiple-cam rings. There is a stationary valve spindle having multiple ports which are in communication with inlet and delivery passages and which successively coact, on rotation of the rotor, with ports in the rotor leading to each of the bores between the pair of plungers therein. In addition, means is provided for twisting one cam ring, about the rotor axis, relatively to the other to vary the phase of reciprocation of each pair of plungers and therefore to vary the pump output.

Preferably each cam ring has a pair of diametrically-opposite high points, and, between them, diametrically-opposite low points, and there are preferably two diametrically-opposite inlet ports (in the valve spindle) and, between them, diametrically-opposite delivery ports, the rotor having an even number of symmetrically-arranged bores—for example, eight.

The adjustment of the one cam ring, in a direction to reduce the pump output, may be effected automatically, in conditions of excess pressure, by a spring-returned plunger (referred to hereinafter as the rack 33) to which the delivery pressure is applied.

Alternatively, the delivery pressure may be applied to a spring-returned plunger (referred to hereinafter by the numeral 57) operating a valve by which, in conditions of excess pressure, the delivery pressure is applied to a plunger (rack 33) by which the one cam ring is adjusted in the direction to reduce the pump output. In this case an adjustable abutment may be provided, for control purposes, for limiting the return movement of the last-mentioned plunger towards the maximum delivery position.

In the accompanying drawings:

Figure 1 is a sectional end elevation of a pump according to the invention, the section being taken mainly on the line 1—1 of Figure 2, with

the upper portion of the hydraulic control shown out of position, i. e., at the top;

Figure 2 is a longitudinal half-section thereof;

Figure 3 is a section of the upper part of the hydraulic control shown in Figure 1 but taken on a plane at right angles to that of Figure 1 and with the plunger 57 omitted;

Figure 4 is a fragmentary plan of the stationary valve spindle showing one of the inlet passages;

Figure 5 is a cross-section, taken on the lines 5—5 of Figures 2 and 4, through the stationary valve spindle;

Figure 6 is a developed view of the adjustable multiple cam;

Figure 7 is a fragmentary view, of the left-hand upper port of Figure 1, showing the parts in the positions they occupy in conditions of excess pressure; and

Figures 8 to 10 are sections taken, respectively, on the lines 8—8, 9—9 and 10—10 of Figure 7.

The drawings show a stationary casing built up of an end wall 12, a cylindrical portion 13 and an end wall 14 which are secured to one another as by means of studs and nuts 15. In the end wall 12 is journalled, as by means of a ball bearing 16, a driving shaft 17 which is keyed at 18 to a rotor 19 in the interior of the cylindrical portion 13. The rotor has in it eight axially-extending bores, of which one (20) appears in Figure 2, and in each bore is a pair of plungers 21, 21 biased apart from one another by means of a compression spring 22. At the outer end of each plunger is secured a bearing pad 23, 23. The one lot of bearing pads coact with a fixed cam ring 24 and the other lot with an angularly adjustable cam ring 25. Each of the cam rings has an operative surface, as shown by Figure 6, giving two high points 27, 27a and two low points 28, 28a, so that the associated plungers will be completely reciprocated twice during each revolution of the rotor.

The adjustable cam ring 25 is carried by a sleeve 29 journalled in the end wall 14 by means of a thrust bearing 30, and it is formed peripherally with rack teeth, indicated at 31, extending over an angular distance which is greater than 90°. The rack teeth are engaged with teeth 32 of an axially-slidable rack 33. By operation of the rack 33 the output of the pump can be varied by varying the phase of reciprocation of the plungers of each pair of plungers.

The rotor 19 has a central bore receiving a co-axial stationary valve spindle 35 which extends through the end wall 14. The rotor also has in

it eight radially-extending ports, of which one is shown in Figure 2 at 36, which respectively communicate with the eight longitudinal bores 20 therein. The inner ends of the ports 36 coact with ports in the valve spindle 35. The latter has two diametrically-opposite ports 37 which are at all times in communication with an outlet or delivery passage 38 provided along the centre of the valve spindle 35. The latter also has a waisted portion 39 enclosed by a sleeve 40 providing an annular passage 41 which is the inlet or supply passage, being fed, by means not shown, from an annular passage 42 through openings of which one is shown at 43.

The axially-inner end of the valve spindle 35 has, communicating with the annular space 41, two passages 45 (Figure 4) terminating with inlet ports 46 (Figures 4 and 5) which are diametrically-opposite one another and spaced symmetrically between the outlet ports 37.

Thus, during each half revolution of the rotor, each radial passage 36 is successively placed in communication with an inlet port 46 and with a delivery port 37, and with diametrically-opposite ports and an even number of plunger bores 20 the parts are at all times pressure balanced.

Figure 1 shows a control rod 48 which is manually adjustable, the rod having a head 49 forming an abutment for the rack 33. In the position shown of the rod 48 the rack is in a position in which the adjustable cam ring 25 is "in phase" with the cam ring 24 (i. e., both rings have their high spots aligned, so that both plungers of each pair move inwardly in synchronism), the pump thus giving its designed maximum delivery. By moving the rod 48 to the right the abutment position of the rack 33 will be correspondingly adjusted to cut down the maximum delivery of the pump below the designed value, when the plungers of each pair are reciprocating out of phase to an extent dependent upon the setting of the control rod.

The rack 33 is shown in this instance in the form of a hydraulic plunger, the space 50 at its operative end communicating with a passage 51 in a body 52. This body 52 has in it a bore 53 communicating with a drain 55 (Figure 3) connected, for example, to the supply tank, and with the parts in the position shown in Figure 1 the passage 51 is in communication with the drain 55 by way of a waisted portion 56 of a plunger 57 slidingly mounted in the bore 53. The latter also communicates with a passage 60 externally connected by a pipe 72 to a passage 61 (Figure 2) connected to the delivery passage 38. The passage 60 is also connected by a passage 62 to the adjacent end of a hydraulic cylinder 63 having therein a plunger head 64 pressed to the position shown by means of a spring 65 adjustably supported by a hollow nut 66, the plunger head 64 being fast with the plunger 57.

Thus the delivery pressure is at all times applied to the plunger head 64 by way of the passage 61, the pipe 72, and the passages 60 and 62.

The nut 66 is set to maintain the plunger 57 in the position shown in Figure 1 whilst ordinary delivery pressures obtain; but when the said pressure exceeds a predetermined value the plunger 57 is moved to the right (Figure 1), thereby disconnecting the passage 51 from the drain 55, and in due course aligning it with a port 68 connected to a bore 69 in the plunger 57, as shown by Figures 7 and 10. The plunger 57 has another port 70, in connection with the bore 69, which when the port 68 is aligned with the

passage 51 is itself aligned with the passage 60. The delivery pressure is then passed from the passage 60 through the port 70, along the bore 69, through the port 68, and along the bore 51 to the operative space 50 to force the rack 33 to the right, as shown by Figure 7, this twisting the cam 25 in a direction to reduce the pump output. When the excess pressure is released by this means the spring 65 returns the plunger 57 to the position shown, thereby again placing the operative space 50 in connection with the drain 55, as shown by Figure 1, and allowing the rack 33 and the cam 25 to return to the position of maximum delivery dependent upon the setting of the control rod 48, the cam 25 being biased to turn in this way by frictional engagement with the rotating pads 23. At the same time the bore 69 in the plunger 57 is placed in communication with the drain 55 by way of a port 54 in the plunger.

If adjustment of the pump (by means of the rod 48) is not required the delivery pressure may be taken directly to the operative space 50, and a spring applied to the rack 33 to balance the delivery pressure until it reaches a predetermined value, as will be well understood, when excess pressure will actuate the rack.

What I claim as my invention and desire to secure by Letters Patent of the United States is:

1. A variable-output hydraulic pump including a stationary casing, a rotor having a circle of axially-extending bores therein, a pair of plungers in each bore, a multicam ring at each end of the rotor, spring means biasing each pair of plungers apart and into contact with the adjacent cam ring, a stationary spindle extending into a coaxial bore of the rotor from one end, said spindle having in it multiple ports which are in communication with inlet and delivery passages and which successively coact, on the rotation of the rotor, with ports in the rotor leading to each of the bores between the pair of plungers therein, a driving shaft extending into the coaxial bore of the rotor from the other end and having a driving connection with the rotor, said driving shaft journaled in said stationary casing, and means for twisting one cam ring about the rotor axis relatively to the other cam ring to vary the phase reciprocation of each pair of plungers and therefore the pump output.

2. A pump, according to claim 1, characterised in that each cam ring has a pair of diametrically-opposite high points and, between them, a pair of diametrically-opposite low points, and in that there are two diametrically-opposite inlet ports in said spindle and, between them, diametrically-opposite delivery ports, the rotor having an even number of symmetrically-arranged bores.

3. A pump, according to claim 1, characterised in that said means for twisting said one cam ring includes an operating plunger to which the delivery pressure is applied.

4. A pump, according to claim 1, characterised in that said means for twisting said one cam ring includes an operating plunger, a valve by which the delivery pressure is applied to said operating plunger, and a spring-retumed plunger to which the delivery pressure is applied and which controls said valve.

5. A pump, according to claim 1, characterised in that said means for twisting said one cam ring includes an operating plunger, a valve by which the delivery pressure is applied to said operating plunger, a spring-retumed plunger to which the delivery pressure is applied and which controls

said valve, and an adjustable abutment for limiting the return movement towards the maximum delivery position of said operating plunger.
